UNITED STATES PATENT OFFICE.

OTTO SCHAUMBERG, OF PITTSBURGH, PENNSYLVANIA.

ELECTRIC HEATING ELEMENT.

Application filed November 1, 1922. Serial No. 598,274.

To all whom it may concern:

Be it known that I, OTTO SCHAUMBERG, a citizen of the United States, residing at Pittsburgh, in the county of Allegheny and State of Pennsylvania, have invented certain new and useful Improvements in Electric Heating Elements, of which the following is a specification.

This invention relates to an electric heating element and has for its object to provide, in a manner as hereinafter set forth, a simple, compact, and very ruggedly constructed electric heating unit so designed and arranged that the resistance wire can be started out from one terminal, namely the negative terminal, and by means of specially arranged ducts, passages and channels can be brought back or extended to the positive terminal in a concealed manner, permitting of the use of one continuous resistance wire beginning at the negative terminal and returning to the positive terminal, which last named terminal is positioned in the same plane, along the side of and parallel to the positive terminal.

If no specially arranged ducts, passages, and channels would be provided in the insulating structure, one of the lead wires, either the positive or the negative, would have to be extended from the finishing turn of the resistance coil along the outside of the heating unit and back to the positive terminal, thus requiring special insulation to prevent the two wires from short circuiting, and furthermore encountering greater danger due to the less substantial construction and the liability of the lead wire being broken and separated from the main resistance coil by the fact that the lead wire is not held in such a firm and substantial manner as disclosed in my invention.

Another important object of my invention is to provide an electric heating element wherein but few essential parts are required to make one complete self-contained heating unit, namely the main body with its ducts, passages and channels, made in its entirety of heat resisting insulating material, and the resistance wire of suitable material and length to obtain suitable resistance, said resistance wire being one continuous length, starting from one terminal and finishing on the other, and the metallic terminals of identical construction.

Further objects of the invention are to

provide a device of the character described, which is simple in its construction and arrangement, strong, durable and efficient in its use, and comparatively inexpensive to manufacture.

To the accomplishment of the above mentioned objects and such other objects as may hereinafter appear, the invention consists of the novel construction, combination and arrangement of parts herein specifically described, and illustrated in the accompanying drawing, wherein is shown an embodiment of the invention, but it is understood that changes, variations, and modifications may be resorted to, which come within the scope of the claims hereunto appended.

In the drawing forming a portion of this specification and wherein like numerals of reference designate corresponding parts throughout the several views:—

Figure 1 is a side view of an electric heating element in accordance with this invention and with a portion shown in section.

Figure 2 is a rear end view thereof.

Figure 3 is a top plan view of the device.

Figure 4 is a longitudinal sectional view of the heating element.

Figure 5 is a transverse sectional view on line V—V, Figure 4.

Referring to the drawing it will be noted that the configuration of the heating element as illustrated thereon is primarily designed for use in connection with a hair waving apparatus as disclosed in my co-pending patent application, bearing Serial No. 520,092, and filing date Dec. 5, 1921, but it will be obvious that the heating element may be of any desired contour to best meet requirements found in practice and in connection with any purposes wherein it is found to be applicable.

The body portion 1 is curved longitudinally and is tapered in cross section, as clearly illustrated in Figure 5, of the drawing. The body portion 1 is constructed from heat resisting insulation material and carries an integrally formed terminal block 2, of the same material, at the rear end thereof.

The upper edge of the body portion 1, adjacent to its connection with the terminal block 2 is formed with a recess 3 to permit of the proper mounting of the terminals 4 and 5, respectively, which are secured, in any suitable manner, in the terminal block 110

2 to extend in parallel, relatively to each other. The rear projecting ends of the terminals 4 and 5 provide the usual means for connecting the heating element with the 5 source of electrical energy, while the forward ends thereof extend in the recess 3 and connect with the lead wires 6 and 7 of the resistance coil 8.

The wire used for constructing the 10 resistance coil 8 is such as to best meet conditions found in practice and is formed from one continuous length in connection with the lead wires 6 and 7.

The resistance coil 8 is mounted on the 15 body portion 1 by passing the lead wire 6 through the aperture 9, which latter extends transversely through the body portion 1 adjacent to the rear upper corner thereof, and securing the said lead wire 6 to the terminal 20 4. The wire is now wound around the body portion 1, as clearly shown in Figure 1, to form the resistance coil 8. After the last lap of the coil has been mounted on the body portion 1 the end of the wire forming the 25 lead wire 7 is passed through the aperture 10, which latter extends transversely through the body portion 1 adjacent to the forward upper corner thereof. The lead wire 7 is then drawn around the rear end of the body 30 portion 1, as indicated at 11, and is inserted to extend rearwardly in the groove or channel 12 which is formed and extends longitudinally in the upper edge of the body portion 1. The lead wire 7 is now passed 35 through the vertical aperture 13, formed in the recess 3 of the body portion 1, and through the angularly disposed aperture 14 communicating with the vertical aperture 13, and opening at the side of the body portion, and is attached to its proper terminal 5.

It will be noted that in my improved heating element but one piece of wire is used to form the resistance coil and lead wires, 45 having its starting point in one terminal and terminating in the second terminal. Such coil structure is only possible by the use of a body portion formed with the channel 12 and apertures, as above described. 50 The arrangement of the lead wires 6 and 7 carry the same in such a way as to eliminate possibility of short circuiting at any point.

While not essential to the proper functioning of the heating element, the device may be 55 provided with a covering of insulating cement which can be painted over the entire body portion 1 to protect the resistance coil

from oxidation and deterioration or from injury due to rough handling and usage.

What I claim is:—

1. An electric heating element comprising a body portion having one edge thereof formed with a longitudinal groove, a terminal block formed integrally with said body portion, a pair of terminals fixed in said terminal block, and a resistance coil consisting of one continuous length of wire and including lead wires connected with said terminals one of said lead wires positioned in said groove, substantially as described and for the purpose set forth. 60

2. An electric heating element for the purpose set forth comprising a curved body portion of heat resisting insulation material, and formed with a longitudinally extending groove, a terminal block formed integrally with said body portion, a pair of terminals carried by said block, and a resistance coil consisting of one continuous length of wire wound on said body portion 75 and including lead wires connected with said terminals, one of said lead wires positioned in said groove, substantially as described. 80

3. In combination, an electric heating element comprising a body portion of heat resisting insulation material, and curved longitudinally, said body portion having its upper edge provided with a recess and with a longitudinally extending groove, a terminal block formed integrally with the rear 90 end of said body portion and extending above said body portion, a pair of terminals carried in said block and projecting into said recess, a resistance coil consisting of one continuous conductor wound on said body portion and including a pair of lead wires 95 connected to said terminals, said body portion provided with a transverse aperture adjacent to its upper forward end, and with a transverse aperture and a combined vertical 100 and angular aperture formed adjacent to the upper rear end of said body portion, one of said lead wires extending through the transverse aperture at the rear end of said body portion, and the other of said lead 105 wires extending through the transverse aperture at the forward end of said body portion and positioned in said groove and extending through said combined aperture, substantially as described and for the purpose set forth. 110

In testimony whereof I affix my signature.

OTTO SCHAUMBERG.
